COMBINED ASH TRAY AND COASTER

John F. Babbitt, Louisville, Ky., assignor to J. V. Pilcher Mfg. Company, Incorporated, Louisville, Ky., a corporation of Kentucky

Application August 14, 1951, Serial No. 16,281

Term of patent 14 years

(Cl. D85—2)

To all whom it may concern:

Be it known that I, John F. Babbitt, a citizen of the United States, residing at Louisville, Commonwealth of Kentucky, have invented a new, original, and ornamental Design for a Combined Ash Tray and Coaster, of which the following is a specification, reference being had to the accompanying drawing, forming a part hereof.

Fig. 1 is a top plan view of a combined ash tray and coaster, showing my new design; Fig. 2 is a side elevational view thereof, with a portion cut away to show a section along line A—A; and Fig. 3 is a perspective view thereof.

I claim:

The ornamental design for a combined ash tray and coaster, substantially as shown and described.

JOHN F. BABBITT.
